SHUTTLE EYE

Philip L. Spencer, Millbury, Mass., assignor to
Watson-Williams Manufacturing Company,
Millbury, Mass., a corporation of Massachusetts

Application May 27, 1933, Serial No. 673,164

5 Claims. (Cl. 139—217)

This invention relates to self threading blocks for loom shuttles and particularly to thread tension devices therein.

It is the general object of my invention to provide an improved construction by which the tension elements will be more securely mounted in the threading block and will be better adapted to resist wear.

More specifically, I provide a separate tubular steel retainer for the tension members, within which the movements of the tension members are confined.

I also provide an improved device for retaining one of the tension springs in operative position but permitting convenient removal thereof.

My invention further relates to arrangements and combinations of parts which will be herein-after described and more particularly pointed out in the appended claims.

20 A preferred form of the invention is shown in the drawing, in which

Fig. 1 is a partial plan view of a shuttle having my improved shuttle eye mounted therein;

Fig. 2 is a front elevation of the eye, looking in the direction of the arrow 2 in Fig. 1;

Fig. 3 is a bottom view looking in the direction of the arrow 3 in Fig. 2;

Fig. 4 is a rear elevation looking in the direction of the arrow 4 in Figs. 1 and 3;

Fig. 5 is an enlarged transverse sectional elevation taken along the line 5—5 in Fig. 1;

Fig. 6 is a side elevation of the retainer for the tension members;

35 Figs. 7 and 8 are end views thereof, looking in the direction of the arrows 7 and 8 in Fig. 6;

Fig. 9 is a side elevation of one of the tension members, and

Fig. 10 is an edge view thereof.

40 Referring to Fig. 1, I have shown portions of a shuttle S having my improved shuttle block mounted therein in the usual manner.

A threading block 20 is provided with a longitudinal thread passage 21 (Fig. 1), a horn 22 and an overlying lip portion 23. A lateral outlet or passage 24 (Fig. 2) is provided below the horn 22, and the thread is retained in the passage 24 by a depending projection 25.

50 Guide members 26 and 27 (Fig. 3) are provided adjacent the outlet 24 and direct the thread to a side opening 28 (Fig. 1) in the shuttle S. The guide members 26 and 27 may be formed of glass or other very hard material which will resist the wear of the thread. A depending hook 29 (Fig.

1) projects laterally and downwardly into the wide entrance portion of the thread passage 21.

At an intermediate point in the thread passage 21 I provide a pair of tension members 30 (Figs. 9 and 10), which are preferably made of thin sheet steel or similar material of segmental cross section. The tension members have outwardly inclined upper end portions 31 to guide the entering thread.

I also provide a retainer 32 (Figs. 6 to 8) for the tension members, said retainer preferably being made of thin sheet steel bent to an oval cross section and provided with elongated thread openings or slots 33 and 34 in the end walls thereof, the openings 33 and 34 extending downward from the top edge of the retainer and the front opening 34 being of greater depth. Holes 35 and 36 are provided in the side faces of the retainer 32 for purposes to be described.

The retainer 32 is pressed into an oval recess 40 (Fig. 5) extending upward from the bottom of the threading block 20 and thereafter forms a permanent part of the shuttle eye.

Tension springs 41 and 42 extend through the openings 35 in the sides of the retainer 32 and their adjacent ends engage the tension members 30. The outer end of the spring 41 is received in a pocket or recess 43 in the side wall of the threading block 20, said recess being aligned with one of the openings 35.

The other spring 42 extends into an opening 44 in the opposite side wall of the threading block 20 and is retained in position by a plate 45 which is inserted from below in an undercut or T-slot 46 (Fig. 3). A cross pin 50 extends through the lower portion of the threading block 20 and positively retains the tension members 30, retainer 32 and plate 45 from displacement. The plate 45 is notched at its lower edge as indicated at 51 (Fig. 4) to receive the pin 50.

When so desired, the retainer 32 may be hardened and tempered before insertion in the recess 40 of the eye 20.

In assembling the parts the retainer 32 is first forced into the oval opening in the threading block 20, the spring 41 is then positioned in the recess 43, the tension members 30 are inserted from below, the spring 42 is placed in position in the opening 44, and the plate 45 is pushed upward from below to retain the spring 42 in the opening 44. The pin 50 is then inserted, securing all the parts in operative relation.

It will be seen that the manufacture of my improved shuttle eye is much simplified by the construction described and particularly by the use

of the retainer 32 and the spring-holding plate 45.

Furthermore, the tension members 30 engage only the inner surface of the retainer 32, which, as previously stated, is to be made of steel or other material which more effectively resists wear than the bronze castings from which the eyes 29 are usually machined. As the tension members 30 are the only movable parts which can cause 10 wear of the shuttle eye, the life of the shuttle eye is much prolonged by my improvements. It has been found that such tension members engaging directly with the bronze casting will rapidly form notches or recesses in the casting on the sharp 15 edges of which fine thread, such as silk or rayon, are easily cut or broken.

Having thus described my invention and the advantages thereof, I do not wish to be limited to the details herein disclosed otherwise than as 20 set forth in the claims, but what I claim is:—

1. In a shuttle, a threading block having a longitudinal thread passage therein and having a recess extending upward from the bottom of said block in said passage and closed in part at 25 its upper end, a pair of vertically disposed tension members, a tubular retainer for said tension members slidably insertable in said recess from below, and means to secure said tension members in said retainer and said retainer in said recess, 30 said retainer being formed of thin sheet metal and having elongated thread slots extending downward from the upper edges of opposed wall portions thereof.

2. In a shuttle, a threading block having a 35 longitudinal thread passage and having a recess extending upward from the bottom of said block in said passage, a pair of vertically disposed tension members mounted in said recess, a spring for one of said tension members, an opening in said

block for said spring, a plate to close said opening, said block having guideways in which said plate is slidable, and means to hold said plate in closing position.

3. In a shuttle, a threading block having a 5 longitudinal thread passage and having a recess extending upward from the bottom of said block in said passage, a pair of vertically disposed tension members mounted in said recess, a spring for one of said tension members, an opening in said 10 block for said spring, a plate closing said opening, and means to hold said plate in closing position, said plate being removably mounted in an undercut recess in one side wall of said block.

4. In a shuttle, a threading block having a 15 longitudinal thread passage and having a recess extending upward from the bottom of said block in said passage, a pair of vertically disposed tension members, a tubular retainer for said tension 20 members, a spring for one of said tension members, a plate to hold said spring in operative position, said block having guideways in which said plate is slidable, and means to secure said retainer, said tension members and said plate 25 in said block.

5. In a shuttle, a threading block having a longitudinal thread passage and having a recess extending upward from the bottom of said block in said passage, a pair of vertically disposed tension members, a tubular retainer for said tension 30 members, a spring for one of said tension members, a plate to hold said spring in operative position, said block having guideways in which said plate is slidable, and a single pin in said 35 block extending crossways of said retainer, said plate and said tension members and holding all of said parts in operative relation in said block.

PHILIP L. SPENCER.
